UNITED STATES PATENT OFFICE.

BONAVVENTURO IZZO, OF PATERSON, NEW JERSEY.

RAILROAD GATE.

1,419,856.

Specification of Letters Patent. Patented June 13, 1922.

Application filed August 23, 1921. Serial No. 494,731.

To all whom it may concern:

Be it known that I, BONAVVENTURO Izzo, a citizen of the Kingdom of Italy, residing at Paterson, in the county of Passaic and State 5 of New Jersey, have invented new and useful Improvements in Railroad Gates, of which the following is a specification.

This invention relates to a railway crossing gate, the general object of the invention 10 being to provide means for operating the gate by the train so that the gate will be closed by the train approaching the crossing and will be opened by the train when leaving the crossing.

Another object of the invention is to provide means for sounding an alarm in the cab 15 of the engine when the train approaches a crossing.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying 30 drawings wherein like characters denote like or corresponding parts throughout the several views, and in which:—

Figure 1 is a view of a part of a railroad track and a crossing showing the application of the invention.

Figure 2 is an enlarged sectional view 35 through a part of the gate and the operating means.

Figure 3 is an enlarged detail view.

Figure 4 is a view of the part carried by the train.

Figure 5 is a sectional view through this 40 part.

Figure 6 is a sectional detail view of part of the gate.

Figure 7 is a diagrammatic view of the 45 alarm means.

In Figure 1, A indicates the railroad track and B the crossing. C indicates a portion of an engine on the track and D indicates the two gates for controlling the crossing.

In carrying out my invention I locate a 50 housing 1 adjacent the track an appreciable distance from the crossing which carries a vertically arranged shaft 2 which passes through the top of the casing. The outer end of this shaft has secured thereto a vertically arranged roller 3 which is adapted

to be engaged by a member 4 on the train. The lower end of the shaft 2 carries a beveled pinion 5 which meshes with a beveled wheel 6 secured to a stub shaft 7 journaled 60 in the housing. A horizontally arranged cylinder 8 forms part of the housing and a piston 9, located in said cylinder, is connected with the wheel 6 by the piston rod 10 so that the rotary movement of the wheel 65 will cause the piston to reciprocate in the cylinder. A rod 11 is connected with the front end of the piston and passes through the outer end of the cylinder. A coil spring 12 is located on this rod 11 and has one end 70 bearing against a stop 13 on the rod and its inner end bearing against lugs 14 projecting into the cylinder so that this spring will tend to hold the piston in its outer position. 75

A housing 1' is placed adjacent the track on the opposite side of the crossing from housing 1 and this housing 1' has associated therewith an arrangement of parts similar to that of the housing 1. The rods 11 and 80 11' of the pistons have their outer ends connected with the cables 14 and 14' which pass over the guiding roller 15 and through the tubes 16 into the housing 17 of one of the gates D. A pulley 18 is connected with the 85 gate and straps 19 each have one end secured to the pulley and the other end connected with a cable. These parts are so arranged that when a pull is exerted upon one cable the pulley will be rotated in one direction 90 by the strap which is connected with this cable so that the opposite strap will be wound upon the pulley. A weight 20 is connected with the gate for insuring its remaining in opened and closed position. The two 95 gates are operatively connected together so that the movement of one gate is transmitted to the other.

It will thus be seen that when a train approaches the crossing the part 4 thereon will 100 strike the roller 3 so as to cause the same to rotate and thus revolve wheel 6 to cause the rod 10 to retract the piston 9 so as to pull upon the cable 14 and rotate the pulley 18 by means of the strap 19. This action will 105 lower the gate, as shown in full lines in Figure 2. After the train passes the spring 12 will return the parts associated with the housing to normal position and thus slack the cable 14, the gates remaining closed due 110 to gravity. Thus the gates are automatically closed at the approach of the train and

after the train passes the crossing the part 4 will strike the roller 3' of the other housing so as to retract the piston 9' and thus pull upon the cable 14' to revolve the pulley 18 5 back to its normal position with the gates in open position. After part 4 on the train leaves the roller 3' the spring 12' will return the parts to normal position with cable 14' slack, ready for the next train to operate the parts in front of the crossing to lower the gates.

I also provide means for warning the engineer that he is approaching a crossing. Such means are associated with the part 4 15 which is of substantially elliptical shape, as shown in Figure 4, and is formed of spring metal so that the curved part 4' will be contracted when engaged by the roller and this contraction movement will force inwardly the spring plunger 21 so as to cause 20 the same to strike the switch operating part 27 and close the switch 28 of the circuit 29 which includes the alarm 30 so as to sound said alarm, thus notifying the engineer that 25 he is approaching a crossing. Part 4 is provided with a flange 4" for bolting the part to a part on the engine.

It is thought from the foregoing description that the advantages and novel features 30 of my invention will be readily apparent.

I desire it to be understood that I may make changes in the construction and in the combination and arrangement of the several parts, provided that such changes fall within the scope of the appended claims.

What I claim is:—

1. In combination with a railroad crossing gate, a rotatable member placed adjacent the track, one on each side of the crossing, means 40 on the train for engaging said members to

rotate the same, means for converting the motion into a reciprocating motion, means for lowering the gate by such means when the first member is engaged by the train and for raising the gate when the second member 45 is engaged by the train and signal means on the train actuated by the engagement of the part on the train with the rotary members.

2. In combination with a railroad crossing gate, a housing located along the track, one in front of the crossing and one in rear of the crossing, a vertically arranged shaft in each housing having its upper end projecting beyond the top of the housing, a roller on said projecting end, a wheel located in each housing and geared to the shaft, a cylinder connected with each housing, a piston in each cylinder, a piston rod connecting each piston with the wheel so that the rotary movement of the wheel will reciprocate the piston, a rod connected with the piston and extending through the outer end of each cylinder, spring means for normally holding the pistons in their outer positions, a drum on the gate and flexible means for connecting the outer ends of the last mentioned rod with said drum.

3. In combination with a railroad gate, means along the track for actuating the same, a part on the train for engaging such means to operate the same, such means including a contractile part, a spring plunger connected with said contractile part and a circuit including a switch closed by the plunger when the part is contracted and a signal connected with the circuit.

In testimony whereof I affix my signature.

BONAVVENTURO IZZO.
